UNITED STATES PATENT OFFICE.

EDOUARD BELIN, OF PARIS, FRANCE.

SYSTEM OF FACSIMILE TELEGRAPHY BY WIRELESS SIGNALS.

Application filed September 3, 1924, Serial No. 735,605, and in France September 27, 1923.

The invention relates to the transmission of pictures and more particularly to the radio transmission of pictures which are composed in whole or in part of infinite gradations of light and shade between maximum and minimum illumination. In a co-pending application Serial Number 8,022, filed February 9, 1925, it has been pointed out that such a method of transmission is applicable to both line drawings, manuscripts, and the like which may be described as having "high contrast" and photographs, lithographs and the like, which have relatively low contrasts between adjacent portions.

The condition of any given portion of a photographic picture is a direct index of the degree of illumination of the corresponding portion of the object photographed, and may be expressed mathematically as a function thereof and varying proportionately thereto: that is, the picture may vary either in relative translucency at the point in question, or in relative thickness if a gelatine coating be employed. This relative illumination may therefore be expressed by a current which varies in amplitude proportionately therewith. If successive points of the picture be explored by a translating apparatus to so express the variations of illumination, the current resulting will be of a character similar to a telephone current, but non-oscillatory, being at times constant for an appreciable period and at times varying from minimum to maximum in periods anywhere from several seconds to a very small fraction of a second, and may according to the present invention be used to modulate by action either upon the potential of a direct current, or the amplitude, or the frequency or both of a carrier current.

In the system of facsimile telegraphy, described in my U. S. Patent No. 915,154, transmission is effected by the slight differences in level of the surface of a relief photograph or the like. These differences in level, by their action upon a variable resistance, vary the intensity of a weak current passing through the resistance proportionally to such differences in level, and therefore, according to the differences of light and shade of the photograph or the like to be transmitted. This weak varying current must be

suitably amplified before it acts upon the wireless transmitting apparatus proper. The amplifier employed for this purpose is of the resistance type and has no condensers or transformers through which the varying continuous current in the circuit must pass so that due to the absence of resistances the amplified currents or electrical variations faithfully follow the differences in level of the surface explored.

It is likewise possible with the present invention to employ a translucent positive or negative picture having relative gradations of light and shade, and to produce therefrom a varying current which faithfully follows in amplitude the lights and shades of the picture, and then at the receiving end to obtain from this current a photographic positive or negative.

This invention comprises a transmitting station at which is located means for generating a direct or a carrier wave current, and apparatus adapted to impose upon such current modulations which are a function of the relative light or shade of the picture it is desired to transmit; and a receiving station at which is an apparatus adapted to receive the modulated current from the transmitting station, and to produce a beam whose luminosity varies as a function of the modulations of such current, which serves to translate these modulations into photographic effects.

The transmitting and receiving apparatus are synchronized with respect to each other by ways and means well known in the art. Since such means form no part of the present invention, they are not shown nor described in detail.

The preferred form of this apparatus has been found in practice to give excellent results where the communication between the two stations was established through the natural media; but obviously the system is likewise applicable to work along intervening metallic or other conductors as well.

The accompanying drawings set forth diagrammatically means of accomplishing the invention, and

Fig. 1 shows a transmitting circuit for radio communication with modulation amplifiers and a modulating and oscillating tube.

Figure 2 is a diagram indicating the ap-

paratus employed at the receiving station.

Figure 3 shows a modified transmitting circuit in which the microphone is supplied with an alternating current.

- 5 In Fig. 1 the variable resistance M, which in construction may be a carbon pile such as a microphonic transmitter button, is acted upon in accordance with the varying level of the surface explored, in the manner shown 10 in my U. S. Patent No. 915,154. As the speed of the record is not so high as to set up free oscillations of the movable parts of the microphone by shock excitation in any substantial degree its resistance changes in 15 exact correspondence with such irregular or non-oscillatory variations; and correspondingly affects the current flowing from the local source 2, through it and the regulating resistor 1. This current is applied to the grid 20 and filament of an amplifying tube A; and by its potential creates corresponding and amplified variations in the potential across the plate circuit resistance 5, from the plate battery 4. These variations are in turn amplified by the second tube B and succeeding tubes if any, with resistance coupling indicated at 8 and biasing battery at 6. It will be understood that any suitable number of these tubes may be employed, until the resultant current is sufficient to serve for modulation. In practice, such an amplifier of three or four properly regulated stages is sufficient to modulate a transmitting system of several hundred watts when the resistance 30 of the variable resistor—a microphone button—only varied a few ohms (equivalent to three or four watts at most) under the pressures; this represents very feeble variations of the grid potential for the first tube. 40 Such an amplifier may be used if the microphone is fed with continuous current. It is likewise possible to employ an alternating current whose amplitude varies with the pressures exerted on the aforesaid variable resistance, and such alternating current may be amplified by the ordinary amplifier with transformers or resistance coupling as usually employed in a wireless telephonic transmitting station. However, 45 where the modulating current is a direct current which may remain constant for appreciable periods of time the modulation of the carrier wave by such irregular variation of the direct current cannot be likened to that 50 which obtains in wireless telephony, as an oscillatory wave or a wave of musical frequency is not superposed for modulating the high frequency oscillation. It is proposed rather to translate irregular differences in 55 level in the surface explored into corresponding irregular variations of the amplitude or of the frequency or of both amplitude and frequency of the high frequency oscillations. 60 A striking difference between the modulating current produced from the ordinary tele-

phonic transmitter and that produced by this system is due to the tendency of the diaphragms of such transmitters to make independent oscillations; whereas in the present case, the amount of movement in either direction is not oscillatory or of true wave form but a precise function of the irregular variations in the picture, and is in no wise independent thereof.

Figure 1 shows one very suitable example 75 of a circuit arrangement which is a type of the absorption system well known in wireless telephony.

The resistance 8 placed in the plate circuit of the last amplifying stage is connected 80 between the filament and the grid of a group of tubes one of which is shown at C, termed absorption tubes, whose filament plate resistance constitutes a variable non-reactive 85 impedance. Biasing batteries 9 are placed in the grid circuits of the tubes so as to obtain suitable modulation which is thus made as proportional as is possible. The filament plate circuit of tube C includes the inductance coil 14. The oscillating or control valve D is connected to deliver into this latter circuit high frequency oscillations by means of the grid inductance 10 in electromagnetic relation to the portion of coil 14 utilized as a 90 plate inductance, with grid leak 12 and condenser 11, plate condenser 15, and plate battery 13. Since the internal resistance of the absorption tubes varies with the current from the microphone, the resistance of the output circuit of these tubes must vary with 95 the relative illumination of the original object.

Furthermore, since the impedance of the high frequency circuits varies, in which the absorption occurs, a change of wave length 105 results whose effect is peculiarly favorable for reception, as will be described hereafter.

Whereas wireless telephone reception may take place without a heterodyne (the high frequency wave serving only as a carrier for the audible frequency oscillation which reproduces the voice) for receiving signals transmitted by the present method a heterodyne is used to establish a beat frequency 110 with the received high frequency oscillation. It has already been stated that the oscillations change amplitude each time that the pressure upon the variable resistance changes. These changes of amplitude are to be reproduced at the receiving station as 115 modulations on a relatively very low frequency, thus necessitating the use of a heterodyne. On the other hand, the wave length of the transmitting station also changes (very feebly it is true) with the modulation, so that the low frequency produced by the beats of the heterodyne itself varies both in 120 amplitude and in frequency. The wave received at the indicating apparatus passes from 1500 cycles to 400 or 500 cycles, for ex- 125 130

ample, when there is pressure on the variable resistance.

In the system set forth in the aforesaid patents, reception of pictures to produce a range of light and shade takes place by the aid of an oscillograph, traversed by the emergent beam from a lamp and shutter device responsive to the transmitted current, and it will be easily understood that an oscillograph, by reason of its low yet appreciable inertia, is very sensitive to the variations in frequency of the received current, much more so than to the variations in intensity of the current.

15 At high frequencies, say above 1500 cycles, the movement will be very small for a given intensity of reception. For lower frequencies, however, this movement may become considerable. Therefore in the range below 20 approximately 1500 cycles may be found all the degrees of freedom required for use in this apparatus.

It will be understood that it is possible, for receiving, to add together the two effects, 25 viz changes of intensity and changes of frequency; moreover, that the record produced by the luminous spot of the oscillograph can be controlled by changing the frequency of the heterodyne. This latter may be effected 30 by using instruments whose own period is variable or by employing receivers which are more or less tuned. It will also be understood that positives or negatives may be produced by adjusting the frequency of the 35 heterodyne below or above that of the oscillator at the transmitting station.

It is possible to feed the transmitting microphonic circuit at the transmitter with alternating current of audible frequency, 40 which may then be amplified by means of the amplifiers ordinarily used in telephonic transmitting stations. In this case, referring to Figure 2, there is used a small oscillator E of musical frequency (for example, 45 600 cycles), having the grid inductance 21, plate inductance 20, plate battery 22, and regulating plate condenser 23. By means of a variable contact on its plate inductance, this oscillator feeds a photographic variable 50 resistor M of the same type as that described above, with an oscillating or alternating current, according to its internal resistance. The local circuit of the resistor is then arranged across the grid and filament of the 55 first amplifying tube A or in the primary of a transformer 24 which acts upon such tube A as shown in the diagram. The amplifier is similar to those employed in wireless telephony stations, while the modulation process 60 may be any suitable process. Reception takes place without a local heterodyne, and the low frequency oscillation of 600 cycles is directly modulated by the resistor having an ordinary receiver with or without re- 65

It has also been stated that oscillograph instruments are above all sensitive to changes in frequency; by the last arrangement described, variations of amplitude of the low frequency oscillations received are 70 alone obtained. The frequency of the low frequency oscillator of the transmitter may also be acted upon in the same manner as described for the transmitting station in the 75 first arrangement.

It is apparent that this invention is not restricted to the particular circuits and arrangements shown and described, and I do not desire to limit myself except within the 80 scope of the appended claims.

Having thus described my invention, what I claim as new and desire to secure by Letters Patent is:

1. The method of transmitting gradual, 85 irregular, non-oscillatory electrical variations representing gradual variations in light and shade between successive points on a picture by radio frequency carrier waves and receiving the same with an oscillograph receiver responsive to variations in frequency of a relatively low frequency carrier current, which comprises transforming the electrical variations into corresponding variations in frequency of a radio frequency 90 carrier current, transmitting the radio frequency carrier current to a receiving station and at the receiving station heterodyning said radio frequency carrier waves to produce a variable frequency carrier current of the said relatively low frequency to which 95 the oscillograph is responsive and varying in frequency in accordance with the variations in frequency of the radio frequency carrier wave. 100

2. The method of receiving frequency 105 modulations of a carrier wave and recording the same in direct or inverse magnitude at will, which comprises, a combining with the received modulated waves heterodyning waves of a frequency above or below the 110 limits of variation of frequency of the received waves to cause the beat frequency produced thereby to vary directly or inversely, according to the kind of record desired, and actuating a recorder in accordance with the 115 frequency variations of the beat waves.

3. In a system for the transmission of pictures, a source of electrical oscillations, means for transforming the different intensities of illumination of different successive points on the picture to be transmitted into corresponding different values of frequency of said electrical oscillations, a receiving station, means at the receiving station for receiving said oscillations, a heterodyne oscillator at the receiving station arranged to heterodyne with the received oscillations to produce beat oscillations varying in frequency, in accordance with the variations in 120 frequency of the received oscillations, and 125

130

an oscillograph recorder at the receiving station differentially responsive to the different frequencies of the variable frequency beat waves.

5. 4. In a system for modulating high frequency currents with gradual non-oscillatory electrical variations comprising, an audion

modulator tube, an audion tube oscillator and high frequency oscillation circuit therefore, and an inductance coil partly included in the oscillation circuit and wholly included in the output circuit of the modulator tube.

In testimony whereof I affix my signature.
